UNITED STATES PATENT OFFICE.

CHARLES KING, OF LOUISIANA, MISSOURI, ASSIGNOR OF ONE-FOURTH TO WILLIAM B. HALEY
AND ONE-FOURTH TO ROBERT A. MAY, BOTH OF LOUISIANA, MISSOURI.

HOLDER FOR A SERIES OF SMALL RECEPTACLES.

No. 919,182.

Specification of Letters Patent.

Patented April 20, 1909.

Application filed May 20, 1908. Serial No. 433,983.

To all whom it may concern:

Be it known that I, CHARLES KING, citizen of the United States, residing at Louisiana, in the county of Pike and State of Missouri, have invented certain new and useful Improvements in Holders for a Series of Small Receptacles, of which the following is a specification.

The present invention provides a novel device for cooling food and drink in places where ice is not obtainable, but which are supplied with either a spring, a well, or a cistern.

The invention consists of a bucket provided with a cover which is not liable to be easily displaced and which may provide a tight joint to prevent water from entering the bucket, should the same be submerged in the water of a well, cistern or the like. A series of receptacles are adapted to be placed within the bucket, each being designed to receive food, drink or the like to be cooled. A holder is provided for securing the receptacles to admit of their being handled conveniently, as when placing the same in the bucket or removing them from the bucket.

For a full understanding of the invention and the merits thereof and also to acquire a knowledge of the details of construction and the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a perspective view of a bucket embodying the invention, parts being broken away. Fig. 2 is a perspective view of the holder, the dotted lines showing a series of receptacles in position. Fig. 3 is a horizontal section of the holder, showing a receptacle in position, the dotted lines illustrating the position of the retainer when turned aside to permit the buckets being placed in the holder or removed therefrom.

Corresponding and like parts are referred to in the following description and indicated in all the views of the drawings by the same reference characters.

The bucket 1 is preferably constructed of

sheet metal and may be of any size or shape and is supplied with a bail 2. The upper portion of the bucket is formed with a screw thread to match a corresponding screw thread of the rim of the cover 4, thereby admitting of said cover being tightened to prevent displacement and to insure a close joint to exclude moisture from the bucket in the event of the same being submerged in the water of a well, spring, or the like. A band 5 strengthens the upper portion of the bucket and is fitted thereto immediately below the screw threaded portion. The ears to which the bail is attached are connected to the sides of the bucket below the screw thread portion 3 so as not to interfere with the operation of the cover when tightening or loosening the same. It is to be understood that packing of any kind may be provided to insure the formation of a tight joint between the cover and bucket when desired.

The bucket is intended to receive a series of receptacles 5 which serve as containers to receive the food, drink or other article to be cooled. The receptacles 5 may be of varying heights to admit of their advantageous use, each being provided with a cover to exclude matter of any kind and to prevent the flavor of one food being impaired by the flavor of another in the event of the receptacles being open or not supplied with covers.

A holder is supplied as an essential part of the appliance in order to receive the series of receptacles and admit of their being easily and conveniently placed in the bucket or removed therefrom. The holder consists of a rigid frame and a pivoted frame. The rigid frame comprises vertical bars 7 and end bars 8, the latter being deflected intermediate of their ends. The pivoted frame is in the nature of a retainer and consists of a vertical bar 9 and end bars 10, the latter being pivoted at 11 to the end bars 8 of the rigid frame. When the pivoted frame is turned to bring its vertical bar to a point midway of the vertical bars 7, the several bars 7 and 9 are equidistant and embrace the sides of the receptacles so as to confine and hold the same in superposed or vertical relation. When the pivoted frame is turned aside, as indicated by the dotted lines in Fig. 3, the receptacle 5 may be either placed in position in the holder or re-

2 moved therefrom. After the receptacles have been placed within the holder, as indicated by the dotted lines in Fig. 2, and the pivoted frame has been turned to the 5 position indicated in Fig. 2, and by the full lines in Fig. 3, said receptacles are confined and the holder may be lifted and lowered into the bucket or removed from said bucket as may be required.

10 The food, drink or other article to be cooled is placed in the receptacles 6, which are then closed by fitting the covers thereto, said receptacles being placed in the holder and made secure by turning the pivoted 15 frame or retainer, after which the holder with the receptacles is lowered into the bucket and the latter closed by fitting the cover 4 thereon. The bucket is suspended or placed within a well, spring, cistern or 20 the like, to permit the contents to cool. The cover 4 by reason of its screw thread connection with the bucket is not liable to be easily displaced, and a tight joint may be obtained by interposing a packing between the cover and bucket, as will be readily understood.

Having thus described the invention, what is claimed as new is:

30 1. The combination with a bucket, a series of receptacles, and a holder for said receptacles, the same consisting of complementary frames, one of said frames being

pivoted to be turned aside to admit of the receptacles being placed in position or removed from the holder and consisting of a single 35 vertical bar and end bars, and the other frame comprising vertical bars and end bars, the vertical bars adapted to embrace the sides of the receptacles and the end bars to extend across the ends of the pile of receptacles.

2. In a device of the character set forth, a holder for confining a series of receptacles, said holder consisting of a rigid frame and a pivoted frame, a rigid frame comprising 45 relatively vertical bars and horizontal or end bars, and a pivoted frame comprising a single vertical bar and end bars, the latter being pivoted to the end bars of the rigid frame.

3. In an appliance of the character specified, a holder comprising a rigid frame, and a pivoted frame, the rigid frame comprising vertical bars and inwardly converged end bars, and the pivoted frame having its end 55 bars pivoted to the end bars of the rigid frame at their point of convergence.

In testimony whereof I affix my signature in presence of two witnesses.

CHARLES KING. [L.s.]
